United States Patent

Des. 240,606
Patented July 20, 1976

240,606

HAND HELD OPTICAL CHARACTER RECOGNITION SCANNING UNIT

Robert B. Koenig, Dallas, Tex., assignor to Recognition
Equipment Incorporated, Irving, Tex.

Filed Sept. 26, 1974, Ser. No. 509,712

Term of patent 14 years

Int. Cl. D10—07

U.S. Cl. D10—46

FIG. 4

FIG. 3

FIG. 1

FIG. 2

FIG. 5

FIG. 1 is a left side elevational view of a hand held optical character recognition scanning unit showing my new design, the right side being a mirror image thereto;

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for a hand held optical character recognition scanning unit, as shown and described.
